BRAKE FOR A DIE SINKING MACHINE

John M. Rusnak, West Hartford, Conn., assignor
to Niles-Bement-Pond Company, Hartford,
Conn., a corporation of New Jersey

Application October 12, 1937, Serial No. 168,634

6 Claims. (Cl. 188—74)

This invention relates to die sinking machines and particularly to a die sinking machine of the type having means for actuating the cutter in an arcuate path of different predetermined radii.

Another object of the invention is to provide an improved braking means for the spindle which will apply a predetermined braking effect upon a driving member for the spindle and independently of the force exerted by the operator upon a hand operating lever.

And another object of the invention is that this braking means is interlocked with the circuit of the motor for the cutter rotating spindle to open the circuit when the brake is being applied.

The features of construction forming the present invention constitute improvements upon the die sinking machine described and claimed in the patent to Bayrer 1,354,942 granted October 5, 1920.

With the above and other objects in view, the invention may include the features of construction and operation set forth in the following specification and illustrated in the accompanying drawings.

In the accompanying drawings annexed hereto and forming a part of this specification, I have shown the invention embodied in a motor driven die sinking machine of the vertical spindle universal type, but it will be understood that some of the features of the invention can be embodied in other machine tools and that the drawings are not to be construed as defining or limiting the scope of the invention, the claims appended to this specification being relied upon for that purpose.

In the drawings:

Figure 1 is a complete side elevation of a die sinking machine in which the present invention is incorporated.

Fig. 2 is a vertical sectional view taken centrally through the tool spindle and showing a part of the cutter supporting and moving head.

Fig. 3 is a vertical sectional view showing the remainder of the cutter supporting and moving head and the driving motor for the tool spindle.

Fig. 4 is a horizontal sectional view taken centrally through the operating eccentrics for the movable head for the cutter.

Fig. 5 is a plan view of the brake operating mechanism for the tool rotating spindle, and

Fig. 6 is a central vertical section taken on the plane of line 6—6 of Fig. 5.

In the above-mentioned drawings there has been shown but one embodiment of the inven-

tion which is now deemed preferable, but it is to be understood that changes and modifications may be made within the scope of the appended claims without departing from the spirit of the invention.

Briefly and in its broadest aspect, the invention may include the following principal parts: First, a base having a column portion; second, a work supporting table adjustable vertically and horizontally to different operative positions on said column; third, a head slidably supported within a fixed upper part of the base secured to the column and movable in a vertical plane in circular paths of different radii; fourth, a cutter spindle and supporting sleeve vertically disposed within the movable head and axially adjustable toward and from the table; fifth, a motor mounted on the movable head for rotating the spindle within its sleeve in any adjusted position thereof; sixth, a brake movable into a position against a driving pulley for said spindle; seventh, spaced adjustable eccentrics supported within the upper fixed portion of said base for moving the head in closed paths while maintaining the axis of the cutter spindle at all times vertical; eighth, means to simultaneously adjust the eccentricity of said eccentrics; ninth, means to simultaneously rotate the eccentrics in any adjustable position so that a cutter in said spindle may be moved in arcuate paths of any predetermined radii; tenth, a cylindrical bearing formed in the movable head for engagement with one of said eccentrics; and eleventh, an arcuate bearing member partially engaging the other of said eccentrics and supported adjustably within the head for limited free angular and linear movements in any direction.

Referring more in detail to the figures of the drawings, I provide a base 10 having a column portion 11 on which is adjustably mounted for vertical movement a work supporting bracket or knee 12. On the upper horizontal surface of this bracket or knee 12 is slidably mounted a saddle 13 carrying a work supporting table 14 movable transversely thereon. A work piece W being operated on may be clamped in position on this table 13. The above described work supporting and positioning means are or may be those usually forming parts of a standard die sinking machine and may be adjusted by means of hand wheels 15, 16 and 17 respectively for operating the knee 12, saddle 13 and table 14.

The base 10 at the upper end of the column portion 11 is in the form of a fixed head portion 18 having two spaced parallel side surfaces 19

between which is movably mounted a cutter supporting head 20 presently to be more fully described. Within this movable head 20 is a vertically disposed cutter spindle 21 mounted adjacent one end. Preferably and as shown in the figures, this spindle 21 is rotatable within a vertically adjustable sleeve 22 so that the axial position of the spindle 21 may be widely adjusted toward and from the table 14. A cutter or tool 23 may be clamped by any usual means to the lower end of the spindle 21. In order to effect vertical movements of the sleeve 22 and cutter spindle 21, there is provided a vertical screw 24 engaging a nut 25 secured to an intermediate portion of the sleeve 22 so that by rotation of this screw 24 by any suitable means (not shown) the sleeve 22 and spindle 21 may be moved vertically up or down.

At the upper end of the cutter spindle 21 are provided longitudinal splines 26 extending within a compound gear member 27, there preferably being a splined collar 28 directly surrounding and fitting the spline portion 26 of the spindle 21 and to which the gears 27 may be keyed. The collar 28 is mounted upon suitable anti-friction bearings 29 mounted within the movable head 20 so that the spindle 21 in any vertical position may be rotated by rotating the collar 28 and gears 27. Engageable with the gears 27 upon the collar or sleeve 28 are gears 30 slidably mounted upon an intermediate shaft 31, either gear of which may be slidably moved into driving relation with one or the other of the gears 27 surrounding the spindle 21. The upper end of the intermediate shaft 31 has secured thereto a driving pulley 32 shown in the form of a sheave for multiple V belts, there preferably being portions of different diameters to provide two or more speed changes for the spindle 21.

At the opposite end of the movable cutter head 20 is vertically mounted a driving motor 33, this preferably being directly secured to a slidably mounted bracket 34 adjustable upon the movable head by means of a suitable horizontal guideway 35. The bracket 34 may be held in adjusted position by means of a transverse clamping or locking screw 36. For convenience in adjusting the bracket 34 toward and from the spindle driving pulley 32 adjusting screws 37 are provided permitting accurate adjustment of the bracket 34 and motor 33 for the particular belts 38 being used. The motor shaft 39 at its upper end is provided with a pulley 40 connected by the belts 38 to the pulley 32 upon the intermediate shaft 31. From the above described construction the cutter spindle 21 may be rotated at four different rotative speeds for each speed of the motor 33.

In order to effect limited braking action upon the cutter rotating pulley 32 when it is desired to stop rotation of this spindle, there is provided a brake shoe 41 of arcuate form and movable to a position to bear upon the driving pulley 32 within one of its belt sheaves as shown. This brake shoe 41 is secured rigidly to a member 42 in the form of a generally rectangular block slidably mounted within the movable head 20 and in its released position is forced away from the pulley by means of light springs 43 surrounding headed rods 44 secured to the brake shoe member 42 and having their springs bearing against abutments formed on the movable head 20. As shown in Fig. 5, the brake shoe member 42 is slidably mounted within a recess formed horizontally within the movable head 20 and extending longitudinally therein. To retain the brake shoe 41

and member 42 slidably in position a cover plate 45 is secured to the head 20 closely adjacent the walls of the recess. The brake shoe therefore while normally retracted from the pulley 32 by its springs 43 may be moved toward and into contact with the pulley by moving the member 42.

Within the brake shoe member 42 and extending from its end remote from the pulley 32 is slidably mounted an actuating member 46 which, as shown in Fig. 6, has a small flange at its inner end and is enclosed by an adjusting screw 47 threaded into member 42. Interposed between the inner end of the actuating member 46 and the member 42 is a heavy coil compressive spring 48. From the above it will be seen that pressure exerted against the actuating member 46 will cause the spring 48 within the brake shoe member 42 to be compressed beyond its initial load which will therefore force the brake shoe 41 toward and into contact with the surface of the pulley 32. In its opposite position the actuating member 46 will have its inner flange end bearing against the inner face of the adjusting screw 47 which limits outward movement and extension of the spring 48. To force the actuating member 46 in a direction to force the brake shoe 41 against the pulley 32 there is provided an adjustable screw 49 longitudinally threaded into and movable with the actuating member 46 having a head 50 upon its outer end. Preferably a locking nut 51 is provided on the screw 49 to maintain adjustments of the screw. The desired movement of shoe 41 can be obtained by adjusting the screw 49 relative to the actuating member and by oscillating a cam 52.

Adapted to engage against the outer face of this head is a portion of the rotatably mounted cam or member 52 having cut-away portions as shown in Fig. 6, one of which engages the head 50. This cam 52 is mounted upon an intermediate portion of a transversely extending shaft 53 mounted for oscillatory movements within the movable head 20. By oscillation of this shaft 53 to different angular positions the cam 52 in one position will force the brake member 42 toward the pulley 32 and in another oscillated position will permit outward movement of the shoe 41 and member 42 by the light springs 43 referred to above.

In order to effect oscillation of the cam 52, a short lever 54 is keyed to one end of the shaft 53, there being a reach arm 55 extending forwardly from lever 54 and engaging the upper end of an intermediately pivoted hand lever 56. In one position, therefore, of the lever 56 the brake 41 will be released and in another position the brake will be forced tightly against the pulley 32 to effect a firm braking effect upon the pulley and spindle 21. The pressure of the brake shoe 41 against the pulley 32 will be wholly determined by the amount of compression of the spring 48 within the member 42 and in no way will be affected by the pressure applied by the operator to the hand lever 56.

Mounted adjacent the shaft 53 on which the cam 52 is mounted is a switch 57, this switch being in the control circuit for starting and stopping the spindle rotating motor 33. This switch 57 is of the button type having a bridge member 58 movable to circuit opening and closing positions relative to the switch contacts. In the depressed position of the button 59 the switch 57 will be open and in the normal or extended position of the button the switch will be closed. Movable against the button 59 is one end of a

small bar or rod 60, the opposite end of which is pointed and engaging the periphery of a collar 61 on the shaft 53. In the oscillated position of the shaft 53 which releases the brake 41 the bar 60 enters a V notch in the collar 61 and thus permits the button 59 of the switch 57 to be extended by a spring within the switch to move the bridge member 59 into a position to close its circuit. In the other oscillated position 10 of the shaft 53 in which position the brake 41 is being applied to the pulley 32 the bar 60 rides out of the notch provided in the collar 61 which depresses the button 59 of the switch 57 and thus opens the control circuit for the spindle driving motor 33. Motor 33 therefore cannot be started while the brake 41 is being applied.

The movable head 20 within which is mounted the cutter spindle 21 and sleeve 22 is mounted upon eccentric sleeves 62 and 63, one of which is shown in Fig. 2, and the other in Fig. 3. These eccentric sleeves 62 and 63 are similar to each other and form parts of eccentrics of the compound type, there being two eccentrics, one within the other relatively adjustable to vary the eccentricity of the eccentric sleeve relative to the shaft 64 on which it is mounted. The construction of these eccentrics is similar and their means for adjusting their eccentricity is similar so that but one of these eccentrics will require description. 30 As will be seen in Figs. 2, 3 and 4, the sleeves are mounted upon inner eccentric surfaces 66 formed integrally with the shafts 64.

Preferably these inner eccentrics 66 formed upon the shafts 64 have bearing portions or journals 67 on opposite sides of the eccentric surfaces 66 and are supported in fixed position for rotation within the fixed head portion 18 of the base, there being a cover plate 68 rigidly fastened to the base and forming one side of the fixed head 18 in order 40 to permit assembly of these eccentrics. Surrounding each integral or inner eccentric 66 is the eccentric sleeve 62 and 63. These sleeves have internal gear teeth 69 formed therein and meshing with the teeth of a pinion 70 upon a shaft 71 extending through the inner eccentrics 66 coaxially of their journal portions 67.

The eccentrics 62 and 63 shown in Figs. 2 and 3 are rotatable simultaneously by means of gears secured to one end of their supporting shafts 64, 50 these gears 72 meshing with a common intermediate gear 73. The intermediate gear 73 for driving the eccentrics 62 and 63 is mounted rotatably upon a stud 74 fixed within the cover plate 68 and provided with a worm wheel 75 keyed thereto 55 and meshing with a horizontally disposed worm 76. The worm 76 is supported horizontally within the cover plate 68 so that rotation will slowly rotate the eccentrics simultaneously and will therefore actuate the movable spindle head 20 in 60 a closed arcuate path. The worm 76 by means of which the eccentrics are simultaneously rotated may be manually rotated by a hand wheel 77 on the forward end of its shaft 78. Also if desired a small motor 79 may be mounted on a portion of 65 the fixed head drivingly connected to the worm shaft 78 through a suitable telescoping and jointed connection with the shaft 78.

In order to vary the radius of the path of movement of the movable head 20 the shafts 71 on 70 which the adjusting pinions 70 are mounted have at their outer ends driving gears 80 of the same diameter and number of teeth as the gears 72 for the inner eccentrics 66. These latter gears 80 are in mesh with a common intermediate gear 81 75 so that by rotation of this intermediate gear 81

while the worm wheel 75 and eccentric driving gears 72 are maintained relatively fixed the radius of movement of the cutter head may be varied.

To effect this adjustment, a worm wheel 82 is keyed so as to be rotatable with the intermediate gear 81. This worm wheel 82 may be mounted on a sleeve formed on worm wheel 75 and meshes with a worm 83 housed within and having its shaft supported within a member 84 rotatable with the worm wheel 75 for the eccentric driving 10 gears 72. By means of a hand wheel 85 on the outer end of a short shaft connected drivingly with the worm 83 the eccentric sleeves 62 and 63 may be widely varied relative to their axes of rotation on the inner eccentrics. 15

The path of movement of the head 20 and spindle 21 may be widely varied by rotation of wheel 85 and during operation of the spindle the member 84 within which the worm 83 is mounted rotates about the axis of stud 74 with rotation of 20 gear 75. In universal die sinkers as at present made the mountings for eccentrics such as shown at 62 and 63 have each been fixed and similar one to another. It has been found, however, that due to unavoidable inaccuracies in manufacture or 25 inaccurate alignment and adjustment of the parts supporting the movable head 20 that a cramping action may occur in the bearings which prevents smooth and easy rotation of the eccentric driving mechanism to move the tool in an arcuate path. 30 It is therefore a feature of the present invention to eliminate the possibility of the eccentrics 62 and 63 upon which the movable head 20 is supported becoming cramped by lack of accurate adjustment or misalignment or unavoidable errors in manufacture. As shown in Fig. 2, the eccentric sleeve 62 adjacent the cutter spindle 21 is directly mounted within a fixed cylindrical surface formed directly within the movable head 20. This front eccentric, therefore, accurately controls the vertical and lateral positions of the cutter head 20 at all times. The rear eccentric 63 more remote from the cutter spindle 21 is mounted within the head 20 by a special and improved bearing member and support shown most clearly in Fig. 3. 35 40 45

It will be seen by reference to Fig. 3 that the movable head 20 is cut away to form an enlarged recess surrounding the sleeve 63 for the rear eccentric, there being a small arcuate surface 86 integral with the movable head 20 and bearing 50 55 against the lowermost portion of sleeve 63. The upper surface of the eccentric sleeve 63 upon which the weight of the movable head 20 is principally supported bears against an inserted arcuate member 87 which is so mounted within the head 20 that it is free to adjust itself within limited distances either laterally or by tilting or by movement angularly about a vertical axis.

Preferably this arcuate bearing member 87 may have a central recess 88 within its upper portion within which may loosely fit a vertically disposed stud 89 adjustably threaded within the movable head 20. A ball 90 of relatively large diameter inserted within the recess 88 and within the recessed lower end of the stud 89 is positioned 60 65 between bearing plates 91, one plate being mounted in the arcuate member 87 and the other directly thereabove in the stud 89. With this construction and with the ball 90 forming the weight supporting member, the arcuate member 87 is free to 70 tilt slightly about a horizontal axis or about a vertical axis or may move slightly laterally within the recess 88. By means of this freedom of movement cramping action between the eccentric sleeves 62 and 63 and the movable head 20 in any 75

adjustment or in any driving position thereof is prevented.

In operation of the machine and after the work piece W has been mounted on table 14 and positioned properly the hand wheel 85 is rotated to adjust the radius of movement of the head 20. This adjustment is indicated by the graduations 92 on member 84. The motor 79 may then be operated to simultaneously rotate the eccentric sleeves 62 and 63 together with the inner eccentric 66. In lieu of the motor 79 for actuating the tool 21 in its arcuate path the hand wheel 77 may be rotated.

What I claim is:

13. 1. A spindle brake for machine tools comprising in combination, a spindle, a driving pulley therefor, a brake shoe movable into and out of contact with said pulley, a cam adjacent said shoe, means to oscillate said cam, an actuating member for said shoe, and a spring housed within said shoe and disposed between said actuating member and cam, whereby oscillation of said cam in one direction compresses said spring and forces said shoe against said pulley.
18. 2. A spindle brake for machine tools comprising in combination, a spindle, a driving pulley therefor, a brake shoe movable into and out of contact with said pulley, a cam adjacent said shoe, means to oscillate said cam, an actuating member for said shoe, a spring housed within said shoe and disposed between said actuating member and cam, and means within said shoe whereby the compression of said spring may be varied.
33. 3. A spindle brake for machine tools comprising in combination, a spindle, a driving pulley therefor, a brake shoe movable into and out of contact with said pulley, a cam adjacent said shoe, means to oscillate said cam, an actuating member for said shoe moved by oscillation of said cam, a compressive spring housed within said shoe and disposed between said actuating member and cam, and means within said shoe to adjust the com-

pression of said spring, whereby oscillation of said cam in one direction will force said shoe against said pulley with a force determined by the adjustment of said spring.

4. A spindle brake for machine tools comprising in combination, a spindle, a driving pulley therefor, a brake shoe movable into and out of contact with said pulley, an actuating member for said shoe housed within said shoe, a spring within said shoe and forcing said actuating member away from said shoe, means limiting the movement of said actuating member away from said shoe, and a cam oscillation of which forces said member toward said shoe and said shoe resiliently against said pulley.

5. A spindle brake for machine tools comprising in combination, a spindle, a driving pulley therefor, a brake shoe movable into and out of contact with said pulley, an actuating member for said shoe housed within said shoe, a spring within said shoe and forcing said actuating member away from said shoe, means limiting the movement of said member away from said shoe, a cam oscillation of which forces said member toward said shoe and said shoe resiliently against said pulley, and means normally holding said shoe away from said pulley.

6. A spindle brake for machine tools comprising in combination, a spindle, a driving pulley therefor, a brake shoe movable into and out of contact therewith, a cam adjacent said shoe, means to oscillate said cam, an actuating member for said shoe movable by said cam, a spring disposed between said actuating member and shoe whereby operation of said actuating member by said cam resiliently forces said shoe against said pulley, and means to vary the force exerted against said pulley by said shoe when said cam is oscillated.

JOHN M. RUSNAK. 40
